UNITED STATES PATENT OFFICE

EDWARD W. STOLER, OF MANSFIELD, OHIO, ASSIGNOR TO KELSEY-HAYES WHEEL CORPORATION, OF DETROIT, MICHIGAN, A CORPORATION OF NEW YORK

SELF FEEDING SWAGING ROLL

Application filed March 8, 1929. Serial No. 345,437.

The objects of the invention are to provide an improvement in swaging mechanism for tapering or otherwise reducing the bodies of wire spokes before they are assembled in the hubs and rims of wire wheels.

In my former application, bearing Serial Number 270,283, filed Apr. 16, 1928, roller swaging mechanism is shown by means of which the spokes are propelled through a series of swaging rollers from continuously fed wire stock and finally are cut therefrom of the required length and provided with swaged on heads of the required size.

In the present machine however the spokes are first cut to lengths and headed and the rolls are provided with spoke engaging means which draw the spokes therethrough, and simultaneously shape them by swaging, so as to at once produce a perfectly formed spoke.

The invention includes a hopper from which the spokes are fed by gravity, to a longitudinal platform or support and thence to a pair of swaging rolls, the circumferential edges of which are provided with recesses which engage with the head of the spoke presented, and draw it through the rolls.

A plunger is provided that reciprocates through the bottom of the hopper to project one spoke blank at a time over said platform into a position where its head will be engaged by said rolls.

Also following rolls are provided which seize and draw the spokes from the swaging rolls.

The second named rolls may also comprise finishing rolls if desired.

With these and other valuable objects in view, the invention includes the combination and arrangement of parts and construction of details, hereinafter described, illustrated in the accompanying drawings and specifically pointed out in the claims.

In the accompanying drawings, Fig. 1 is a vertical longitudinal section of the device. Fig. 2 is a bottom plan thereof showing the spoke feeding tube in longitudinal sections. Fig. 3 is a transverse section of the spoke containing hopper and feeding plunger.

Fig. 4 is a transverse section of one of the swaging rolls. Fig. 5 is a plan of one of the completed spokes.

In these views, A is a hopper in which the spokes B—B are received and fed to the platform C in position to be engaged by the plunger D as it reciprocates upon the platform, E and F are the swaging rolls which are provided with grooves G and H in their circumferential peripheries in which the sides of the spokes are formed or tapered as desired.

Upon the circumferential edge of the rolls are shown the transverse grooves I and J respectively which engage with the heads K of the spokes in turn as they are propelled forward over the platform by the plunger D.

For this purpose the heads K are guided into position by means of the groove L at the outer edge of the hopper, in which they are retained by means of the guide bar M which is attached to the hopper by brazing or otherwise.

The plunger may be operated by means of the arm O which is provided with the cap N secured to the arm at P and to which the outer end of the plunger is secured at Q.

The cap reciprocates in the open slot R in the lower part of the hopper wall and is supported therein by the bottom wall S of the hopper.

This arm is operatively connected with the movements of the lower roll by means of the pin T which projects from the outer side thereof and engages on the forward movement of the arm with the groove V in the upper arm W of the forked end thereof.

As the roll revolves to the right as shown by the arrow in Fig. 1, the pin will be released from the groove V and will engage in turn, on further revolution of the roll with the extremity X of the lower arm and will return the plunger to its original position.

This action will be continued as long as any spokes are furnished to the plunger.

The second pair of rolls Y—Y' will then engage with the spoke and these rolls are also provided with grooves Z, Z' across the rolls to engage with the heads of the spokes and

may also be provided with swaging grooves for finishing the spokes.

Any suitable gearing may be employed to drive the rolls.

5 As many pairs of rolls may be provided as are desired to give the spokes the required amount of finish.

The position of the cap N on the arm O may be adjusted by sliding it along the arm 10 O and clamping it in the adjusted position by means of the screw P, threaded into an arm O and passing through the slot N' in the cap N.

Having described the invention what I 15 claim as new and desire to secure by Letters Patent is:

1. In an automatically acting spoke swaging machine, said spokes being provided with heads, a narrow hopper open at its lower end 20 and provided with guide means for the heads of said spokes, a platform under the said hopper adapted to receive one spoke at a time therefrom, a pair of swaging rolls adjacent to the forward ends of said spoke while lying upon said platform, and a plunger horizontally reciprocatable over said platform to move a blank from the hopper and a reciprocatable arm secured to said plunger, said arm being provided with a forked outer 25 end, the upper arm of said fork being provided with a recess in its lower edge and a pin or engaging member secured to the lower swaging roll and revolvable therewith to engage with said recess in said arm, and to move said plunger forward, said pin thereafter engaging with the lower arm of said fork to move said arm rearwardly.

2. In a swaging machine for swaging headed wire spokes, the combination of a pair of 40 combined feeding and swaging rolls, said rolls being provided with head engaging means, a hopper, a platform thereunder upon which said spokes fall by gravity therefrom, a plunger reciprocable over said platform 45 through the bottom of said hopper to project a blank spoke over said platform in such a position that the head of said spoke will be engaged by the head engaging means of said rolls, a feeding arm attached at its outer end 50 to said plunger and having a vertical fork at its inner end, the upper member of said fork being provided with a notch, and a pin operatively connected with one of said rolls and adapted to engage with said notch once 55 in each revolution of said roll to move said plunger forward, and thereafter to engage with the lower fork member on its return movement and return said arm and plunger.

In testimony whereof, I hereunto set my 60 hand this 2nd day of March, 1927.

EDWARD W. STOLER.
